ILLINOIS.

ELEVATOR DRIVE MECHANISM.

No. 833,385.

Specification of Letters Patent.

Patented Oct. 16, 1906.

Application filed June 14, 1905. Serial No. 265,144.

To all whom it may concern:

Be it known that I, STACY B. HART, a citizen of the United States, residing at Peoria, in the county of Peoria and State of Illinois, have invented certain new and useful Improvements in Elevator Drive Mechanism; and I do hereby declare that the following is a full, clear, and exact description of the invention, which will enable others skilled in the art to which it appertains to make and use the same.

This invention has reference more particularly to power-transmitting mechanism for connecting a rotary member of an elevator with the auger of an auger conveyer communicating therewith; and the object which I have in view is to provide means for detachably connecting the elevator member to the auger, so that variations in the alinement of the said elevator member and auger will not affect the transmission of power from one to the other.

A further object of my invention is to provide an extension for the auger for conveying the material in the auger conveyer nearer to the elevator-boot, if desired.

In the accompanying drawings, which illustrate my invention, and in which similar reference characters indicate similar parts in the several views, Figure 1 is a vertical sectional view of the lower part or boot of a grain-elevator and the adjacent parts of a threshing-machine, wherein my invention is employed to connect a power-driven auger in a grain-receptacle of the threshing-machine with the lower sprocket of the grain-elevator; Fig. 2, a horizontal sectional view of a portion of Fig. 1 on the line *a a* thereof; Fig. 3, a vertical sectional view of the lower portion or boot of the elevator on the line *b b* of Fig. 2 looking in the direction indicated by the arrow. Fig. 4 shows the elevator-sprocket and a portion of the auger with their axes of rotation *y y* and *x x*, respectively, considerably out of alinement and illustrates the manner in which the connection herein described adapts itself to the variable alinement of said parts. This figure further shows an extension for the auger, which may be used to increase the effective length thereof and convey the grain nearer to the elevator-boot.

1 represents a grain-receptacle of a threshing-machine, and 2 an auger journaled there-

in at intervals by means of the brackets 3, 55 which said auger during the operation of the threshing-machine is rotated, so as to convey the grain that is received in the receptacle to one end thereof, from whence it is discharged into the lower part or boot 4 of an elevator. 60 This elevator, as can be seen by reference to the drawings, is detachably fastened to the outlet end of the receptacle 1, and when the elevator is operated from the auger in the receptacle, which is a common practice, it is 65 necessary to provide such a connection between the auger and the driven member of the elevator, so that the operation is not affected by inaccurate adjustment of the elevator on the outlet end of the auger-receptacle 1. 70

Heretofore it has been the custom to secure the lower sprocket of the elevator on a sleeve that telescoped the end of the auger-stem, so that the sprocket rotated in the boot independent of any connection therewith, and consequently the inaccurate adjustment of the elevator would be less liable to affect the operation. This construction, however, has been found to possess some very material disadvantages, which my invention is designed to obviate.

In my construction I fix in the boot 4 of the elevator and in approximate alinement with the auger-stem 5 the stub-axle 6, upon which is mounted the lower sprocket 7 of the 85 elevator, which said sprocket, together with the upper sprocket of the elevator, carries the chain 8, upon which are fastened the flights 9, which travel in the elevator-tubes. 10

Connecting the sprocket 7 to the auger-stem 5 is a flexible or compensating connection constructed as follows: On that face of the sprocket 7 nearest to the end of the auger-stem 5 is a knuckle-joint 11, which said knuckle-joint is connected by the links 12 to 95 a second knuckle-joint 13 on the end of the sleeve 14. This sleeve is adapted to telescope the end of the auger-stem 5, as shown, and is secured thereon by means of the setscrew 15. This connection, as can be seen, 100 will permit of the axes of rotation of the sprocket 7 and the auger-stem 5 being considerably out of line and adjusts itself to the variable alinement of the parts which it connects without affecting the transmission of 105 rotation from one to the other.

In attaching elevators to threshing-machines it is often desirable to increase the

effective length of the auger, so as to convey the deposit in the auger-receptacle nearer to the boot of the elevator. This may be accomplished by providing the sleeve 14 (lengthened, if necessary) with a flight or vane 16, inclined similarly to the flights of the auger 2. This flight or vane 16 on the sleeve 14 forms a prolongation of the flight of the auger 2 and can be made to carry the grain as close to the boot of the elevator as is desired.

The advantages which my invention possesses over the constructions heretofore used result from the fact that the sprocket 7 is permanently placed in the elevator-boot and does not have to be changed or adjusted whenever the elevator is removed, and the frequent troublesome and difficult removal and replacing of the sprocket and the consequent adjusting of the chain which carries the elevator-flights is done away with. In the constructions heretofore used when the elevator was detached the chain which carried the flights often became tangled and wedged in the tubes, all of which disadvantages, as can be seen, are overcome by the use of my invention.

Although I have shown and described my invention in certain precise forms and as applied to a particular form of grain-elevator used in connection with a threshing-machine, I am aware that the same idea can be applied to advantage in various other constructions, in many of which it will be necessary to modify the herein described and shown construction to suit the purposes for which it is adapted, all of which different applications and modifications I contemplate.

Having thus fully described my invention, what I claim, and desire to secure by Letters Patent of the United States, is—

1. In an elevator drive mechanism, the combination of an auger or screw conveyer, a rotary elevator member substantially in line with the auger or screw of the conveyer, and a multiple universal joint connecting the rotary elevator member with the said auger or screw.

2. In an elevator drive mechanism, the combination of a rotary elevator member with an endless bucket or flight carrier mounted thereon, a rotary conveyer member adjacent said elevator member, and a multiple universal joint connecting said elevator member with the said rotary conveyer member.

3. In an elevator drive mechanism, the combination of an elevator, a conveyer-trough communicating with the elevator, an auger or screw journaled in the said conveyer-trough, a rotary member in the elevator substantially in line with the auger or screw of the conveyer, and a multiple universal joint

connecting the rotary elevator member with the auger or screw of the conveyer.

4. In an elevator drive mechanism, the combination of a sprocket mounted in and carried by the boot of the elevator, a rotary conveyer member adjacent the said sprocket, and a multiple universal joint connecting the said sprocket with the said rotary conveyer member.

5. The combination with an auger or screw conveyer, of an extension therefor comprising a sleeve telescopically mounted on the stem of the auger or screw, and a vane carried by said sleeve extending in a similar direction to the flights of the auger or screw.

6. In an elevator drive mechanism, the combination of an auger or screw conveyer, an extension therefor, comprising a sleeve telescopically mounted on the stem of the auger or screw and a vane carried by said sleeve extending in a similar direction to the flights of the auger, and a rotary elevator member connected to said sleeve.

7. In an elevator drive mechanism, the combination of an auger or screw conveyer provided with a vane-carrying sleeve extension mounted on the stem thereof, a rotary elevator member and a multiple universal joint connecting said auger or screw extension with said rotary elevator member.

8. In an elevator drive mechanism, the combination of an auger or screw conveyer provided with a vane-carrying sleeve extension mounted on the stem thereof, a rotary elevator member substantially in line with the auger or screw, and a multiple universal joint connecting the said auger or screw extension with the said rotary elevator member.

9. The combination with a threshing-machine of a grain-receptacle, an auger journaled to operate in said receptacle, an elevator operating in conjunction with the grain-receptacle, and receiving the deposit from the grain-receptacle in the lower part or boot thereof, a drive-sprocket on a stub-axle in the boot of the elevator, around which said sprocket travels the chain by which the elevator-flights are carried, a knuckle-joint on the said sprocket, an adjustable and detachable sleeve on the stem of the auger, a knuckle-joint on the said sleeve, and links connecting the said knuckle-joint of the sprocket and the said knuckle-joint of the sleeve, substantially as and for the purposes specified.

In testimony whereof I have affixed my signature in the presence of two witnesses.

STACY B. HART.
